A. C. GOODMAN AND HENRY FESSLER, OF CANTON, ASSIGNEES TO THEMSELVES AND HENRY FOLTZ, OF STARK COUNTY, OHIO.

Letters Patent No. 71,737, dated December 3, 1867.

IMPROVEMENT IN RAILROAD-GATES.

The Schedule referred to in these Letters Patent and making part of the same.

TO ALL WHOM IT MAY CONCERN:

Be it known that we, A. C. GOODMAN and HENRY FESSLER, (assignors to ourselves and Henry Foltz,) of Canton, in the county of Stark, and in the State of Ohio, have invented certain new and useful Improvements in Gates for Railroads; and do hereby declare that the following is a full, clear, and exact description thereof, reference being had to the accompanying drawings, and to the letters of reference marked thereon.

In the annexed drawings, making part of this specification, A represents a platform, across which the sills or sleepers B B are placed. I I represent the rails of a railroad-track, which are secured upon the ties or sleepers B B. C represents a gate, composed of a bottom bar, with a series of vertical teeth secured in it, which said gate is so placed that its bottom bar lies under the rails I I, being provided with suitable bearing and caps, which allow the gate to partially rotate backward and forward, or rise and fall to one side or the other. Connected to the under side of this bar of the gate is a weight, D, which tends to keep the gate in an upright position. Lying across and beneath the track, upon each side of the gate, and a short distance from it, are two crank-shafts E, which have a bar, F, running up from their centres, standing in a vertical position in the centre of the track. The cranks of these shafts extend down below the platform, and are connected at their ends, by means of rods G G, to a projection, at a, on the under side of the weights D. H represents a spring-bar, secured at one end to the crank-shaft E. This bar H is provided with a notch, at x, as seen. This gate is intended to rise and fall to one side or the other, when the train approaches, to allow it to pass over freely.

When a train approaches the gate, this cow-catcher strikes one of the upright bars F, which turns the crank-shaft E, causing the rod G to operate the gate, so that it will fall from the train. When the gate falls, the spring-bar H, with its notch, catches one of the teeth of the gate and holds it down until the train passes. As the train passes over, a projection upon the rear end of the rear car strikes against the bar H and causes it to release the gate. As soon as the gate is released, the weight D immediately brings the gate to a vertical position. It will readily be seen that, as a train approaches from either direction, the gate will fall from the train and rise again as soon as it has passed over.

The object of this gate is to keep cattle and hogs, &c., from the track, while it allows trains to pass over. These gates may be used at any and all of the crossings of roads or streets upon railroad-tracks.

Having thus fully described our invention, what we claim as new, and desire to secure by Letters Patent, is—

1. The gate C, provided with a weight, D, which causes it to assume a vertical position when not confined, as and for the purpose set forth.
2. The arrangement of the crank-shafts E with their bars F, connecting-rods G G, and the gate C, as and for the purpose specified.
3. The arrangement of the spring notched bar H with the crank-shaft E and gate C, as and for the purpose set forth.

In testimony we claim the foregoing, we have hereunto set our hands, this 22d day of April, 1867.

A. C. GOODMAN,
HENRY FESSLER.
